UNITED STATES PATENT OFFICE.

THOMAS H. PARRY, OF INDIANAPOLIS, INDIANA, ASSIGNOR TO PARRY MANUFACTURING COMPANY, OF INDIANAPOLIS, INDIANA, A CORPORATION OF INDIANA.

VEHICLE SEAT-FASTENER.

1,149,682.

Specification of Letters Patent. Patented Aug. 10, 1915.

Application filed September 12, 1914. Serial No. 861,338.

To all whom it may concern:

Be it known that I, THOMAS H. PARRY, a citizen of the United States, residing at Indianapolis, in the county of Marion and 5 State of Indiana, have invented certain new and useful Improvements in Vehicle Seat-Fasteners, of which the following is a specification.

The object of this invention is so to secure 10 vehicle seats to the bodies of the vehicle that they may be readily removed for greater compactness in shipment, and afterward easily and quickly fastened to the bodies in position for use by the dealers or users who 15 generally are not skilled workmen.

The object also is to provide a better braced, stronger and more durable seat-support and body-connection, which is particularly desirable for such top-vehicles as have 20 their tops secured to and supported by the seats.

I accomplish the above, and other objects which will hereinafter appear, by the mechanism illustrated in the accompanying drawing, in which—

Figure 1 is a top plan view of a piano-box body with a seat attached thereto in accordance with my invention. Fig. 2 is a vertical section on the line 2—2 of Fig. 1, looking toward the rear end of the body, and Fig. 3 is a fragment in vertical longitudinal section on the line 3—3 of Figs. 1 and 2.

Like characters of reference indicate like parts throughout the several views of the drawing.

The sills 4, floor 5 supported thereby, and panels 6 are all of usual and well known construction.

7 are the seat risers, 8 the bottom of the seat which has an opening through it into the usual curtain-box below the seat. This box comprises a bottom 9, sides 10 and ends 11.

At each corner of the box, extending 45 through it from the bottom 8 of the seat to and resting upon the corresponding sills 4, are the posts 12.

The bottom 8 of the seat rests upon and is supported by the risers 7 in conjunction 50 with the sides 10 and ends 11 of the curtain-box and posts 12, the ends of the posts being preferably notched to form shoulders upon which the lower edges of the sides of the curtain-box are more solidly supported.

55 My invention lies primarily in the means

for attaching the seat-bottom 8 to its above-named supports. This comprises metal straps 13, there being one for each of the four posts 12 extending vertically against the post from sill 4 to the curtain-box, in the 60 manner shown, and thence obliquely and inwardly, contacting the curtain-box sides to the underside of the seat-bottom 8, and thence outwardly or away from the box and 65 longitudinally of the vehicle-body forming horizontal members 14. The lower ends of the straps 13 are bent outwardly at right angles to form the feet 15 which rest upon the sills 4. The bent members 14 and 15 are each perforated for the passage of bolts 16 70 and 17, respectively, by which said horizontal members are secured, the lower one to the sill and the upper one to the seat-bottom.

The bolts 16 are connected in pairs, at each end of the seat, by metal straps 18, 75 through which the bolts pass securely fastening the ends of the straps to their respective longitudinal members 19 and 20 of said seat-bottom. The latter is framed with said longitudinal members 19 and 20 and transverse end members 21. The straps 18 connect the top ends of the vertical straps 13, through bolts 16, to keep the latter from spreading, and they also prevent the opening up of the joints between the members 80 19 and 20 and ends 21 of the seat-bottom.

In knocking the job down for shipment or storage, the seat is detached by removing the bolts 16, and the assembly and attachment of the seat afterward only requires the 90 replacing of the bolts, which is within the accomplishment of any novice.

By forming the upper ends of the straps 13 inwardly oblique, as shown and described, the seat is better braced against end strains 95 and vibrations than if the straps were straight, and by contact of the outer edges of the straps against the panels 6 of the body the stresses coming through the oblique ends are more effectually resisted, rendering the seat attachment correspondingly stronger and more durable, and better able to resist the strain of rough roads and wind pressure, particularly in those vehicles having tops attached to the seat.

While I have described my invention with more or less minuteness as regards details of construction and arrangement and as being embodied in certain precise forms, I do not desire to be limited thereto unduly or any 105 110

more than is pointed out in the claim. On the contrary, I contemplate all proper changes in form, construction and arrangement, the omission of immaterial elements, 5 and the substitution of equivalents, as circumstances may suggest or necessity render expedient.

I claim:—

10 The combination with a seat, a curtain-box under the seat, a vehicle body having side panels and a bottom sill, and vertical posts extending from the sill to each of the four corners of the seat, of a plurality of upright straps one for each post fastened 15 at one end to the sill and extending thence upwardly in contact with its adjacent post and panel and thence inwardly beginning

approximately at the bottom of the curtain-box obliquely in contact with said curtain-box and thence outwardly forming horizontal ends which contact with the bottom of the seat, metal straps extending transversely of and resting upon the seat-bottom adjacent each end of the latter, and bolts passing through the metal straps the seat-bottom and said horizontal ends. 20 25

In witness whereof, I, have hereunto set my hand and seal at Indianapolis, Indiana, this 9th day of September, A. D. one thousand nine hundred and fourteen.

THOMAS H. PARRY. [L. S.]
